WALL CAKE CUTTER

Edwin R. Seward and William C. Gainer, New Orleans, La., assignors to ASCO Automatic Specialties Corporation, New Orleans, La., a corporation of Louisiana

Filed Oct. 15, 1956, Ser. No. 616,023

2 Claims. (Cl. 166—173)

The invention relates to devices used in drilling wells and is particularly directed to improvements in cleaning and surface finishing devices for removing filter cake and gelled mud from sections of well bores to be cemented.

It is a principal object of the invention to provide a so-called well scratcher, which performs the cleaning effect not by a scraping but by a cutting action.

It is a further object of the invention to provide a well scratcher which covers the full bore of the well hole with one stroke.

Another object of the invention is to provide a well scratcher which can readily be placed in position on the casing and permanently locked thereto, without substantially slowing down the operation.

Other objects and advantages will become apparent from a consideration of the specification and claims.

According to our invention, the cutting elements are formed as thin strips or blades of spring material fixed with their inner ends to the body of a sleeve or collar by riveting, screwing or welding, while their free outer ends lie on a circle of a diameter substantially equal to the diameter of the well bore. Said blades are curved from their fixed to their free ends in circumferential, outward, and upward direction, so that the blades lie on the surface of an imaginary conic frustum; the lower circle of which coincides with the circle of the fixed blade ends, while its upper circle, substantially of the diameter of the well bore, coincides with the circle going through the free ends of the blades. By this formation, the blades are resilient and offer only slight resistance, by bending inwardly, to the downward movement of the casing, thus performing a centering function only, while being more rigid in the opposite direction, thus performing effectively and uniformly the desired cutting action during one upward stroke of the casing string. Near their fixed ends, the blades are provided with open loops by coiling or twisting them, so as to form a narrow winding. This increases the deflectibility of the blades and diminishes the working stresses especially during the cutting stroke.

A sleeve-like carrier of the blades is provided with internal coupling means held in inactive position by releasable locking means for freely shifting this carrier along the casing into the required position; by releasing the locking means, the coupling is brought into operative position and connects the carrier sleeve rigidly to the casing string. The coupling means are formed as a set of internal recesses in the collar or carrier with inclined rear walls co-operating with a set of locking members freely movable in these recesses and being forced, by a slight relative movement, into the narrowing gap between the carrier and the surface of the casing; preferably the coupling means forms a twin set of internal recesses in the sleeve-like carrier with oppositely inclined rear walls co-operating with locking members freely movable axially in these recesses to provide a rigid connection between casing and carrier in both

2

axial directions. We provide manually controllable means for keeping the locking members in inactive position in their recesses while the carrier is positioned on the casing, and for releasing the locking members to activate the coupling. In a preferred embodiment of our invention, said control means are wires threaded through circularly arranged internal guide holes of the carrier sleeve and aligned holes of the locking members, the wires being provided with protruding loops to pull them out of their holes for releasing the locking members.

The locking members of the coupling are, for instance, wedge-like bodies corresponding to the wedge-like shape of the recesses in the carrier sleeve, whereby the inner surfaces of these wedge-like bodies contacting the casing are preferably provided with ratchet teeth to increase the locking effect.

Spring means are provided in the enlarged portions of the recesses and force the locking members, after they have been released, into locking position. Said spring means may be rubber blocks, abutting, with their inner faces, the bases of the twin sets of the locking members.

In the accompanying drawing:

Fig. 1 is a vertical section of a portion of a well, showing in elevation an inserted casing string, and, attached to it, a mud cutting device according to the invention;

Fig. 2 is an enlarged elevation of the mud cutting device;

Fig. 3 is a plan view of this device at the same scale as Fig. 2;

Fig. 4 shows in vertical section the carrier sleeve for the cutting blades with the coupling means and manually controllable means in inactive position;

Fig. 5 shows, partly in section, the locking members of the coupling in inactive position;

Fig. 6 is a similar section showing the locking members released and in activated position;

Fig. 7 is a perspective view of one of the locking members;

Fig. 8 is a vertical section showing another embodiment of the coupling means of the blade carrying sleeve.

In Fig. 1, 10 represents the bore of the well, in which a casing string 11 is inserted. On this casing string, a sleeve-like carrier 12 is arranged, equipped with a series of circularly evenly spaced cutting blades 13, the free outer ends of which cut into the layer or cake of mud 14 covering the genuine strata of the bore wall and shave same off uniformly all around the wall in a single short upward stroke of the casing string. If required, several such carriers may be employed.

As illustrated in Figs. 2 and 3, the cutting blades 13 are formed as thin flat strips of spring material, which strips have in cross section a length of greater dimension than the thickness; their inner ends 15 are riveted or otherwise fixed to the upper rim 16 of the carrier sleeve 12 in uniform spacing so that the greater dimension lies tangentially against said collar in a plane generally parallel to the axis of the collar to provide stiffness against deflection upon upward movement of the collar. Near these inner ends, the blades 13 are provided with open loops 17, formed by twisting or coiling the strips. Then the strips forming the blades 13 are bent circumferentially and outwardly as well as upwardly in a generally helical form, so that their outer free ends are confined by a circle substantially of the diameter of the well bore. Due to this shape and manner of attachment, the blades are deflected inwardly and upwardly with slight resistance when the casing string is being lowered into the well bore, and hold the casing string in accurate alignment with the bore. But when the casing string is being moved upwardly, the blades tend to bend outwardly and downwardly with considerable resistance

70

and cut into the layers of mud, shaving the wall of the well bore effectively and uniformly in a single upward stroke of the casing string.

For both these actions, it is necessary to hold the sleeve-like blade carrier 12 in rigid connection with the casing string. This is effected by special coupling means inside the carrier sleeve, which can be instantaneously brought into locked position where they allow the free shifting of the sleeve along the casing string; when unlocked, they hold securely the sleeve and prevent it from being displaced in axial direction.

The embodiment illustrated in Figs. 4-7 comprises two sets of oppositely arranged wedge-like locking members 19, 20, slidably positioned in two sets of corresponding recesses 21, 22, inside carrier 12. The inner vertical faces of members 19, 20, contact directly the outer surface of the casing string 11 and are provided with ratchet teeth 23, 24, for better gripping action.

The bases 25, 26, of wedges 19, 20, are abutted against springs, preferably rubber blocks 27, arranged in the enlarged middle portion 28 of recesses 21, 22. When springs 27 are held compressed and the wedge-like members are held abutted against them, no coupling between carrier sleeve 12 and casing 11 is effected. But when spring 27 is released as well as members 19, 20, which then may slide in their recesses 21, 22, the rigid coupling is performed automatically.

To serve as controlling means for wedges 19, 20, and simultaneously for springs 27, wires 29, 30 are threaded through holes 31, 32, in wedges 19, 20, and aligned guide holes 33, 34, provided in the side walls of recesses 21, 22. In this position of the wires 29, 30, the wedges 19, 20, and compressed springs 27 are held inactive. But when the wires 29, 30 are pulled out, which can easily and rapidly be done by means of protruding loops 35, 36, the coupling means is released and slips into coupling position. Figs. 5 and 6 show, respectively, the two positions of the coupling.

In the embodiment shown in Fig. 8, one set only of locking members, formed as balls or rollers 40, is arranged in a corresponding set of symmetrically tapered recesses 41. When these balls or rollers 40 are held in the wider middle portion 42 of their recesses, they do not contact the outer surface of casing string 11 and

are therefore inactive. But when freed, they enter into coupling position in both the downward and upward movement of the casing string. The controlling means for members 40 is again a wire 43, preferably provided with an external loop and threaded through holes of members 40 and aligned holes inside carrier sleeve 12.

We claim:

1. A cleaning assembly for well bores comprising a collar rigidly connectable to a string of a casing to be inserted into the bore of a well, and a set of spaced resilient cutting blades fastened to the collar, said blades being flat spring strips curved upwardly and outwardly in a generally helical form, and having in cross-section a length of greater dimension than the thickness, said strips being attached to said collar so that the greater dimension lies tangentially against the collar to provide stiffness against deflection upon upward movement of the collar.

2. A wall cleaner as defined in claim 1, in which the strips forming the cutting blades are provided near their fixed ends with open loops of relatively small diameter, the strip portions entering said loops from the fastening point of the blades being approximately tangent to the outer surface of said carrier, the strip portions leaving said loops having approximately the same angle of tangency, said angle of tangency being adjustable to adjust the average diameter of the surface of said imaginary conical frustum.
